ANTI-SQUEAL SHIM FOR DISC BRAKES

Sigmar Heinz-Peter Micke, 49 Weidtmannstrasse, 54 Koblenz-Metternick, Germany; Gerhard Jakob Roggenbuck, 40 Schuetzenstrasse, 54 Koblenz, Germany; and Harald Gockel, 32 Koppling, 5401 Kaltenengers, Germany

Filed Jan. 24, 1973, Ser. No. 326,283

Claims priority, application Great Britain July 27, 1972

Term of patent 14 years

Int. Cl. D12—16

U.S. Cl. D12—180

Fig. 1

Fig. 2

Fig. 3

FIG. 1 is a front elevational view of an anti-squeal shim for disc brakes showing our new design, it being understood that the rear is a mirror image thereof;

FIG. 2 is an end elevational view thereof; and

FIG. 3 is a front perspective view thereof.

We claim:

The ornamental design for an anti-squeal shim for disc brakes, substantially as shown and described.
